(57) **CLAIM**

We claim the ornamental design for a display screen with a graphical user interface for cloud usage analysis, as shown and described.

DESCRIPTION

A portion of the disclosure of this patent document contains material to which a claim for copyright and trademark is made. The copyright and trademark owner has no objection to the reproduction by anyone of the patent document or the patent disclosure, as it appears in the U.S. Patent and Trademark Office patent file or records, but reserves all other copyrights and trademark rights whatsoever.

FIG. 1 is a front view of a first embodiment of a display screen with a graphical user interface for cloud usage analysis showing our new design.

FIG. 2 is a front view of a second embodiment thereof.

FIG. 3 is a front view of a third embodiment thereof.

FIG. 4 is a front view of a fourth embodiment thereof.

FIG. 5 is a front view of a fifth embodiment thereof; and, FIG. 6 is a front view of a sixth embodiment thereof.

The broken line on the outer boundary of the figures illustrates a display screen and forms no part of the claimed design. All broken lines within the graphical user interface illustrate portions of the display screen with graphical user interface, and form no part of the claimed design.
